UNITED STATES PATENT OFFICE.

CHARLES C. BADEAU, OF BETHLEHEM, PENNSYLVANIA, ASSIGNOR TO ROLLER-SMITH COMPANY, A CORPORATION OF NEW YORK.

CIRCUIT-BREAKER.

1,075,749.

Specification of Letters Patent. Patented Oct. 14, 1913.

Application filed August 11, 1908. Serial No. 447,980.

To all whom it may concern:

Be it known that I, CHARLES C. BADEAU, a citizen of the United States, residing at Bethlehem, in the county of Northampton and State of Pennsylvania, have invented certain new and useful Improvements in Circuit-Breakers, of which the following is a full, clear, and exact specification.

This invention relates to circuit breakers, and more particularly has reference to what are known as overload switches wherein a circuit is automatically opened in case of a load exceeding a predetermined amount, whereby translating and other devices are protected from injury by reason of continued excess of current. Such switches are commonly controlled by means of a magnet coil disposed in the circuit, which upon becoming sufficiently magnetized by a predetermined current, trips a latch or other device thereby permitting a spring or other means to open the switch. In switches heretofore constructed, it has been necessary to make mechanical joints in the circuit between one end of the magnet coil and the switch terminal and between the other end of the magnet coil and the switch blade, and also to provide several turns of the overload coil to cause the opening of the switch.

It is an object of this invention to construct a protection switch wherein one of the switch terminals, the magnet coil and a switch member are formed of a flexible strip of metal, in combination with latching means for holding the switch closed controlled by the magnet coil. Preferably, in the form herein shown, the integral strip comprising the switch terminal, the magnet coil and the switch member is itself formed to provide the desired resiliency for opening the switch when the latch is tripped. By this construction at least two mechanical connections are avoided as well as a number of parts, whereby the construction is simplified and also the cost of manufacture.

A further object of the invention is to simplify the construction of the fixed con-

tact member and reduce the number of terminal joints thereon.

In circuit breakers of the general type to which this invention relates, the switch is provided with main or primary breaking contacts and also secondary contacts, the latter opening last and provided with carbon contact blocks to take the arc and avoid the burning of the primary contacts.

A further object of the invention is to provide means whereby the secondary contact and brush are removably fastened to the same casting which supports the primary brush, thereby permitting the secondary contact to be removed independently of the primary brush.

A still further object of the invention is to provide an improvement in the calibrating devices, whereby the scale is formed on an integral part of the frame supporting the movable switch member and the magnet armature is arranged to register directly with this scale. With this construction the parts are placed in direct relation to each other insuring accuracy and simplicity.

The invention will be more fully understood in connection with the description of the accompanying drawings, wherein—

Figure 1 is a vertical section of a switch embodying the invention; and Fig. 2 is a bottom view.

1 represents a section of a vertical base, or panel-board, having mounted thereon a switch frame comprising a base 2 and two side frames 3, 3. Rigidly mounted between the side frames 3, 3 is a stationary magnet core 4 and pivoted at 5 between the side frames 3, 3 so as to be attracted by the magnet 4 is a U-shaped armature 6, the same comprising a yoke 6 mounted on the pivot 5 and two arms 7 extending inwardly from the pivot 5 toward the core 4. When the core is sufficiently energized the armature 7 will be attracted upwardly toward the core, from the position shown in Fig. 1. The yoke 6 is provided with a cam 8 which engages the end 9 of an operating lever 10.

having the handle 11, pivoted between the side frames 3, 3 at 12. The lever 10 has journaled in its short end 13 at 14 a roller 15, which latter operates the switch arm 16 to close the same through the roller 17 journaled thereon at 18. The switch arm 16 is journaled between the side frames 3 preferably on the ends of the core 4, and it is generally of a U-shape in cross section tapering 10 toward the upper end. Whenever the axis of the roller 15 is slightly above the line connecting the pivots 12 and 18, the switch is closed and kept so until the lever 13 is tripped by the projection 8 of the yoke 6 15 engaging the arm 9 to throw the short arm 15 downward.

19 is a stop carried by the switch arm 16 for the roller 15, to prevent its moving too far.

20 One feature with which this invention is particularly concerned resides in the construction of the movable switch member and the magnet coil whereby the spring, the magnet coil, and the conducting member of 25 the switch are all formed of a continuous strip extending from the bus-bar terminal to the switch contact plate.

20 is a supporting block mounted on the rear of the base 1 to which a bus-bar as 21 30 will be secured, the bus-bar 21 preferably being clamped by a bolt 22 and nuts 23 between two strips 24 which are separated as shown. Each strip is preferably composed of a number of laminæ and after 35 passing through the slot 25 in the base 1 are riveted together as at 26. From 26 these strips pass around the core 4 and thence upwardly to the contact plate 27 to which the strips 24 are secured at their upper 40 end.

28 is a pin carried by the switch arm 16 against which the strips bear.

It will be seen that whenever a sufficient current flows through the strips 24 the core 45 4 will be magnetized sufficiently to attract the armature 7 and thereby open the breaker by withdrawing the roller 15 from engagement with the roller 17. When this occurs the resiliency of the strips 24 forming the 50 magnet coil will throw the switch arm outwardly and downwardly thereby opening the circuit and throwing the handle 11 to the dotted position shown in Fig. 1.

29 is a spring tongue or catch bearing on a 55 resilient material 30 on the movable switch member. Upon release of the movable switch member the spring or catch 29 strikes the hub 60, springs by it and passes under it, and thus cooperates with the resilient 60 material 30 to cushion the blow against the hub 60, and also prevents the movable element from rebounding. The primary contact plate 27 engages a brush 32 which is

mounted in a U-shaped bracket or casting 33 secured to the base 1. To hold the leaves 65 of the brush 32 together a bolt 34 threaded in the U-shaped casting 33 is provided having nut 35 bearing on a wedge block 36.

37 is a secondary contact plate carried by the primary contact plate 27 and bears 70 on a secondary break 38 and also 39.

At the upper end of contact plate 27 is a carbon block 40 bearing on a similar block 41, the contacts 37, 38, 39, 40 and 41 constituting the secondary breaking contacts. 75 The contacts 38, 39, 40 and 41 are all mounted on resilient leaves in the usual manner. The resilient leaves carrying contacts 39, 41, are bolted at 42 to a bent plate or block 43, which is slotted as at 44 and which itself 80 fits upon the U-shaped casting 33 and is bolted to the latter by screws 45. The secondary contact leaves pass through the slot 44 of the secondary supporting block 43 and are screwed to the primary brush 32 85 by a screw 46. The primary brush leaves pass through a slot 47 in the base 1 and are separated and then make direct contact with the other bus-bar connection or cable terminal 48 to be clamped between them by bolt 90 49 and nuts 50. It will be seen that the secondary contact leaves can be removed by simply removing the screws 45 and 46, permitting the secondary terminals to be removed as a whole and renewed or necessary 95 repairs to be made. As the secondary terminals are subject to the greatest deterioration by reason of arcing, this construction is advantageous inasmuch as the secondary contacts can be removed for renewal or repair without dismantling the primary brush.

From the foregoing description, it will be seen that there is a continuous strip between one bus-bar connection or cable terminal 105 and the primary brush on one side of the switch, and between the bus-bar terminal or cable connection and the contact plate on the other side of the switch, thus doing away with the plurality of joints and parts 110 heretofore required.

The armature 7 normally hangs loosely away from the core, and has an extension 52 with a bent end 53 forming an index passing over an arc-shaped extension 55 of side 115 frame 3. This arc-shaped face is provided with a scale as 56 on which the various current values within the range of the switch will be marked. Mounted in a lug 57 on one of the side frames 3 is a set screw 58 120 adapted to bear against one of the sides of the armature 7 slightly below the yoke, so as to adjust the armature toward the core. When the set screw is removed, the armature hangs at its greatest distance from the 125 core, and the pointer 53 being at a position

on the scale corresponding to the maximum rate of capacity of the switch. As the screw is turned to adjust the armature nearer the core, the index 53 moves downwardly on the scale corresponding to the lesser current values. It will be seen that the nearer the armature is held to the core by the set screw the less current is required to magnetize the core sufficiently to attract the armature and open the switch. By this construction the scale is formed upon the part which supports the armature and other parts giving a direct relation of the parts and consequent simplicity and accuracy.

15 Modifications and changes may of course be made in the specific details of construction herein described and illustrated without departing from the scope of the invention.

20 Having thus described my invention, I declare that what I claim as new and desire to secure by Letters Patent, is,—

1. A circuit controlling device comprising a base, a terminal thereon, a flexible resilient circuit controlling member extending from said terminal and having a portion bent to form a single turn magnet coil, said member being laminated throughout its entire length in a direction at right angles to a vertical plane, and a magnet core inclosed by said bent portion.

2. A circuit controlling device comprising a flexible member formed of a plurality of superposed laminæ laminated in a direction at right angles to a vertical plane, said member having a portion bent to form a single turn magnet coil and another portion divided into groups arranged to make fixed contact with one or more intermediate conductors, and a magnet core embraced by said bent portion.

3. A circuit opening device having in combination a movable member, said movable member comprising a flexible strip forming a magnet coil, one end of said strip being adapted for connection with one circuit terminal and the other extending to the making and breaking part of the circuit opening device, a fixed yieldable main contact member adapted for direct connection with the other circuit terminal and being continuous through the main support, a magnet core, and means whereby a predetermined current through said magnet coil causes said flexible member to open the circuit.

4. A magnetically releasable spring-operated circuit controlling device comprising a base, a single flexible resilient circuit controlling member extending from a terminal mounted on said base and having a portion bent to form a single turn magnet coil and a spring, and said member being laminated throughout its entire length in a direction

at right angles to a vertical plane, a magnet core inclosed by said bent portion, means for holding said flexible member in circuit controlling position, and means controlled by the magnet for releasing said member to permit it to move out of said position upon passage of a predetermined current.

5. A circuit opening device comprising a flexible strip containing a plurality of laminæ, the laminæ at one end of said strip being divided into groups adapted to be clamped about an intermediate conductor to make electrical connection therewith, the other end of said strip being movable relatively to the other circuit terminal, a core, a magnet coil around said core and formed integrally with said flexible strip, a mechanism for holding said strip in circuit closing position, and an armature operated by said magnet for controlling said mechanism to open the circuit.

6. A circuit opening device having a resilient flexible strip comprising a plurality of laminæ, the laminæ at one end of said flexible strip being divided into groups adapted to be clamped about an intermediate conductor to make electrical connection therewith, the other end of said flexible strip being movable relatively to the other circuit terminal, a core, a magnet coil around said core and formed integrally with said flexible strip, a mechanism for holding said strip in circuit closing position, and an armature operated by said magnet for controlling said mechanism to open the circuit.

7. In a circuit opening device, the combination of a base support, a stationary contact carried by said support, a frame in fixed relation to said support, a movable switch member pivoted to said frame and carrying a contact coöperating with said stationary contact, means for holding said movable switch member in a position to effect engagement of said contacts, a calibrating scale on a front portion of said frame, means including a magnetic armature supported by said frame for opening said movable switch member, a pointer carried by said armature and projecting so as to move over said scale, and means for adjusting the normal position of the armature relatively to said core to predetermine the opening current for releasing said switch member.

8. In a circuit opening device, the combination with a base support and a contact mounted thereon, of a movable switch member carrying a movable contact, a frame for supporting said switch member, said frame being mounted in fixed relation to said support, means carried by said frame for holding said switch member in a position to effect engagement between said contacts, a calibrating scale on a forwardly

projecting portion of said frame disposed vertically below the line of movement of said switch member, means including a movable magnetic armature supported by said frame for opening said movable switch member, a pointer carried by said armature and projecting so as to move over said scale, and means for regulating the position of the pointer and armature relatively to said

scale to predetermine the current for opening said switch member.

In testimony whereof I affix my signature in presence of two witnesses.

CHARLES C. BADEAU.
